UNITED STATES PATENT OFFICE.

JOHN F. MALTHANER, OF ATLANTA, GEORGIA.

RECORDING-TELEPHONE.

1,335,978.

Specification of Letters Patent.

Patented Apr. 6, 1920.

Original application filed August 3, 1915, Serial No. 43,471. Patented January 7, 1919, No. 1,290,621.
Divided and this application filed December 3, 1915. Serial No. 64,895.

To all whom it may concern:

Be it known that I, JOHN F. MALTHANER, a citizen of the United States, and resident of Atlanta, county of Dekalb, State of Georgia, have invented certain new and useful improvements in Recording-Telephones, of which the following is a specification.

My invention relates to a dictating and recording telephone mechanism and more particularly to a device of that character which may be of convenient size and weight for use on an office desk or similar place.

The mechanism is designed so that it may be used to receive direct dictation for photographic records and also to receive telephone messages from the ordinary telephone receiver to record the same.

This application constitutes an improvement on part of the mechanism shown and described in my pending application Serial No. 876,864, filed December 12, 1914, and a division of my application No. 43,471, filed August 3, 1915.

The objects and novel features of the invention will be apparent from the following description taken in connection with the drawing, in which,

Figure 1 is a vertical cross sectional view of an improved recorder arranged to fit a standard recorder frame, such as an Edison spectacle frame;

Fig. 2 is a bottom plan view of the same;

Fig. 3 is a horizontal cross section of the same on the line 3-3 of Fig. 1;

Fig. 4 is a plan view of the counter-weight and supporting spring for the recorder frame;

Figs. 5 and 6 are perspective views of the improved diaphragms or reeds designed for use on the recorder shown in Figs. 1 to 3; and

Fig. 7 is a diagram showing the circuit connections of the mechanism embodying the invention.

Referring to Fig. 7, the general arrangement of the apparatus is shown in diagram and is described in detail in the parent application above referred to. In general the apparatus comprises a telephone transmitter T of the usual or any preferred design and is provided with a mouth-piece M and with a bracket B upon which the ordinary type of receiver R may be supported. The mouth-piece M consists of a long tube opening into the transmitter casing and a branch

duct D extends from the mouth-piece tube upwardly and opens at the center of the top of the bracket B to register with the opening in the ordinary receiver R. The transmitter T is connected by a wire 10 to a point 60 intermediate the ends of the battery 11 and by a wire 12 to the primary winding 13 of an induction coil I. The other end of the induction coil I is connected by a wire 14 to a contact spring 15. The operation of the 65 spring 15 and the flow of current through the induction coil I may be controlled by depressing a button 18 connected to a contact spring 16 and wire 17. When the button 18 is depressed the contact springs 19 70 and 20 connected to the wires 17 and 21, respectively, are also closed. The wire 20 is connected to one end of a divided circuit, one branch of which includes the secondary winding 22 of the induction coil and the 75 other branch circuit includes the condenser 23 and the receiver 24, the condenser 23 and receiver 24 being connected in series. The wire 25 connects the divided circuit to the winding 26 of a magnetic recorder, the other 80 end of the winding 26 being connected by a wire 27 to one side of the battery 11. A lamp 28 connected by wires 29 and 30 to the wires 10 and 14, respectively, serves as a signal to indicate when the button 18 is 85 depressed as the lamp will be lighted when the circuits are closed at the key 18.

The phonographic record medium is indicated diagrammatically at P and is in the form of a cylinder adapted to be engaged by 90 a stylus 31 carried by a diaphragm 32 which is mounted at its opposite ends on the frame 33.

Referring to Figs. 1, 2 and 3, the frame 33 carries an electro-magnet which consists 95 of a core 34 and a winding 26 surrounding the core. The electro-magnet is designed to vibrate the diaphragm 32 and stylus 31 and the winding 26 thereof is connected to the wires 25 and 27, as heretofore set forth, and 100 is therefore in circuit with the telephone instruments T and 24. The magnet supporting frame 33 consists of a member of magnetic material bent so as to provide a top portion 331 and two downwardly extending 105 parts 332 and 333. At the lower ends of the parts 332 and 333, are two oppositely outwardly extending arms 334 and 335, extending at right angles to the arms 332 and 333, respectively, the arm 335 having a bear- 110

ing portion 336 which extends between two downwardly projecting arms 351 of a casing 35. The pin 352 extends through the arms 351 and 336 and forms the pivot upon which 5 the frame 33 rocks.

The cylindrical casing 35 is threaded at its upper end and closed by a screw cap 36 and near its lower end it has a circular projection 353 which provides a shoulder to support the casing in the usual spectacle frame in a standard Edison phonograph. The walls of the casing 35 are bored to receive insulating bushings 354 which carry the terminal posts 37 by means of which the 10 circuit wires 25 and 27 are connected to the magnet winding 26, mounted on the frame 33. The top portion of the frame 33 extends upwardly into the casing 35 and the horizontal portions 334 and 335 are located below the bottom edge of the casing. 15

The outer end of the frame 33 is yieldingly supported by means of a counter-weight consisting of a solid block of metal 38 which is pivotally supported at the diametrically opposite sides of the casing by the pivot screws 381. A spring plate 39 is fastened to the under side of the block 38 and has the hook 391 at the outer end thereof to receive a rod 40 which connects the 20 plate 39 to a hook 401 near the outer end of the frame 33. In order to adjust the weight 38 and its counter balancing effect I provide a screw 41 which fits a threaded lug 382 on the top side of the weight 38 and which may be set in any adjusted position by a nut 411. It will be obvious that by turning the screw 41 the amount of counter-balancing effect exerted by the 25 weight 38 may be varied and thereby the outer end of the frame 33 may be raised or lowered.

The core 34 of the electro-magnet is secured to the inner side of the top 331 of the frame 33 by a screw 341 which draws the core into close contact with the frame to diminish the magnetic leakage at the joint. The opposite end of the core 42 extends to a point substantially opposite the center of a diaphragm or reed 32 which consists of a 30 flexible, narrow strip of magnetic material. The reed 32 is secured at its opposite ends by screws 321 to the under sides of the parts 334 and 335 of the frame 33. The arms 334 and 335 have their bottom faces 35 cut away for part of the length thereof as at 322 and 323 to leave shoulders on the under sides of those arms which support the reed 32 a slight distance from the arms leaving the narrow air gaps 322 and 323 between the diaphragm and a portion of the frame. By this arrangement the magnetic 40 flux flowing through the pole pieces 332 and 333 will in part flow across or jump the small air gaps 322 and 323 instead of trav-

eling to the shoulders supporting the ends 65 of the reed. In this particular the recorder herein shown is more efficient than the one shown in my prior application above referred to.

The construction of the reed or diaphragm 70 used may be either the one shown in Fig. 5 or the one shown in Fig. 6, the one shown in Fig. 5 being shown in position on the frame 33 in Fig. 1. The reed 32 is narrower at the center than at the ends and 75 approximately at its center it carries a soft iron disk 43 which is provided with a shoulder 431 which acts as a mounting for the sapphire or stylus 31. The soft iron disk 43 may be secured to the reed 32 by 80 two screws, not shown, which pass through the circular portion of the reed at the center, or the center portion of the reed may be provided with integrally bent lugs 432, which engage the opposite sides of the disk 85 43 and hold it in position. In order to dampen the vibrations and prevent cuttings and other foreign substances from getting between the end of the core 34 and the diaphragm 32, I employ a felt washer 44 which 90 surrounds the end of the core and fits between the magnet and diaphragm.

I find that for some purposes a reed constructed of the same width from end to end is preferable. In Fig. 6 I have shown a reed 95 45 of this construction and approximately at its center is mounted a square soft iron disk 46 which is held in place by integral clips 47 and on its under side it has a shoulder for supporting the sapphire or stylus in 100 the same way as shown in Fig. 1. In this form of reed a felt washer 48 is also employed and surrounds the lower end of the magnet core, similar to the washer 44.

The soft iron sapphire mounting is advantageous because it loads the center or approximate center of the reed and eliminates metallic sounds. The amplitude of the reed is also increased and I am able to use a reed of larger gage mild steel than in the 110 device described in my former application. By loading the center of the reed a hammer effect is obtained which is desirable in this apparatus. Primarily, however, the arrangement affords a greater mass of iron 115 for the magnetic flux in proximity to the core of the magnet and being of greater diameter than the core of the magnet it eliminates over-saturation of the reed or dissipation of magnetic flux at the point opposite 120 the core of the magnet.

While I have shown and described the device in detail I do not wish to be limited to the exact construction as set forth. Various modifications may be made therein without departing from the spirit of the invention. 125

Having thus described the invention, what

is claimed and desired to be secured by Letters Patent is:

1. A phonographic recorder comprising a diaphragm of magnetic material, a stylus associated with said diaphragm, an electro-magnet having a soft iron core, one end of said core being in closed magnetic circuit with said diaphragm, the other end of said core being disposed substantially opposite the center of said diaphragm and separated therefrom by a narrow air gap and adapted to vibrate the diaphragm and stylus when the electromagnet is energized. 10
2. A phonographic recorder comprising a diaphragm of magnetic material, a soft iron disk mounted on the under side of said diaphragm, a stylus mounted on the under side of said disk, and an electro-magnet located opposite the upper side of said diaphragm and adapted to vibrate said diaphragm, disk and stylus. 20
3. A phonographic recorder comprising a frame, a diaphragm of magnetic material secured to said frame and having a part separated from said frame by a narrow air gap, a stylus carried on one side of said diaphragm, and an electro-magnet on the frame opposite said stylus for vibrating said diaphragm and stylus, said magnet being secured to the frame with one end in closed magnetic circuit with said frame. 30
4. A phonographic recorder comprising a frame, a diaphragm in the form of an elongated member of magnetic material secured to opposite sides of said frame, a soft iron disk mounted on the outer side of said diaphragm near the center thereof, a lug on said disk, a stylus mounted on said lug, and an electro-magnet carried by said frame and adapted to vibrate said diaphragm, disk and stylus. 40
5. In an apparatus of the class described, the combination of a frame comprising a U-shaped device having arms at opposite sides thereof, a diaphragm attached to the arms of said frame and comprising a reed of magnetic material, a soft iron mounting secured to the reed at its center, a stylus attached to the outer side of said mounting, an electro-magnet secured to said frame and arranged to vibrate said reed and the stylus thereon. 50
6. In an apparatus of the class described, the combination of a stylus, a diaphragm, a frame carrying said stylus and diaphragm, said frame having a portion thereof spaced from said diaphragm by a relatively small air gap to permit flux to pass from the frame to the diaphragm intermediate the ends of the latter, and an electro-magnet secured to said frame and having its core disposed substantially opposite the center of said diaphragm and adapted to vibrate the latter and the stylus thereon. 60
7. In an apparatus of the class described, the combination of a frame, means for piv- 65
- totally supporting the frame at one side, means for yieldingly supporting the frame at the opposite side, an electro-magnet secured to the frame between said supporting means, a diaphragm secured to the frame, a stylus, a soft iron disk carrying said stylus and secured to the other side of said diaphragm near the center, said electro-magnet having a core disposed opposite the center of said diaphragm, and a washer surrounding the end of said core and disposed between the magnet and said diaphragm. 70
8. In an apparatus of the class described, the combination of a diaphragm comprising a strip of flexible magnetic material, a photographic stylus, a soft iron disk intermediate the ends of said diaphragm for connecting said stylus to the diaphragm, a frame for supporting said diaphragm at the ends thereof, and an electro-magnet 80 mounted on the frame and disposed opposite the center of said diaphragm and adapted to vibrate the latter and the stylus thereon. 85
9. In an apparatus of the class described, the combination of an inverted U-shaped frame having laterally extending arms at the bottom thereof, said arms having prominences on the bottom faces thereof, a diaphragm in the form of a reed attached to said prominences on the frame and spaced a slight distance from said arms by a narrow air gap which permits the passage of flux from the frame to the reed, a stylus on the outer side of said diaphragm, and an electro-magnet secured to said frame between the limbs thereof. 90
10. In an apparatus of the class described, the combination of a casing adapted to fit a standard Edison spectacle frame, an inverted U-shaped supporting frame pivoted on and extending into said casing, the limbs of said U-shaped frame having laterally extending arms at the bottoms thereof provided with prominences on the bottom faces thereof, a diaphragm in the form of a flat narrow reed attached to said prominences on the frame and spaced from the remaining portion of the bottom faces of said arms by a narrow air gap which permits the passage of flux from the limbs of the frame directly across the gap to said diaphragm, a soft iron stylus mounting on the outer side of said diaphragm near the center thereof, a stylus carried by said mounting, and an electro-magnet secured between the limbs of said frame and having the core thereof extending close to the center of said diaphragm on the side opposite thereof from said mounting. 110
11. A phonographic recorder comprising a diaphragm of magnetic material, a stylus associated with said diaphragm, an electro-magnet having one pole extended to engage the perimeter of said diaphragm, the opposite pole of said magnet being disposed sub- 125

stantially opposite the center of said diaphragm and separated therefrom by a narrow air gap which permits the passage of magnetic flux from said pole to said diaphragm to be utilized to vibrate the latter and stylus associated therewith.

12. A phonographic recorder comprising a diaphragm in the form of an elongated member of magnetic material, a stylus associated with said diaphragm, an electromagnet having a soft iron core one end of which is in closed magnetic relation with said diaphragm, the opposite end of said core being disposed substantially opposite the center of said diaphragm and separated therefrom by a narrow air gap which permits the passage of magnetic flux to vibrate the diaphragm and the stylus associated therewith.

13. A phonographic recorder comprising an electromagnet having a soft iron core, a soft iron armature, a stylus associated with said armature, one end of said core having a closed magnetic circuit with said armature, the other end of said core being separated from said armature by a narrow air gap which permits an open passage for

magnetic flux whereby changes in magnetic flux in said core are adapted to actuate said armature and the stylus associated therewith when said electromagnet is energized.

14. In an apparatus of the class described, the combination of a frame, means for pivotally supporting the frame at one side, means for yieldingly supporting the frame at the opposite side, an electro-magnet secured to the frame between said supporting means, a diaphragm secured to the frame, a stylus, a soft iron disk carrying said stylus and secured to the other side of said diaphragm near the center, said electro-magnet having a core disposed opposite the center of said diaphragm, and a washer surrounding the end of said core and disposed between the magnet and said diaphragm, said yielding supporting means including a pivoted balance weight and means for changing the center of gravity of the weight relative to its pivots.

In testimony whereof I affix my signature.

JOHN F. MALTHANER.
